HUGH ROSS TOOKER AND HARRY LEIGH TOOKER, OF SANTA MARIA, CALIFORNIA.

PEN OR PENCIL CLIP OR HOLDER.

1,147,199.

Specification of Letters Patent. Patented July 20, 1915.

Application filed August 5, 1914. Serial No. 855,190.

To all whom it may concern:

Be it known that we HUGH ROSS TOOKER and HARRY LEIGH TOOKER, citizens of the United States, residing at Santa Maria, in 5 the county of Santa Barbara and State of California, have invented a new and useful Pen or Pencil Clip or Holder, of which the following is a specification.

This invention has reference to pen or 10 pencil clips or holders, and its object is to provide a device for the purpose which shall be of simple construction with a minimum of parts and operable by one hand of the user for the introduction of the pen or pencil into a pocket and its removal therefrom and the certain holding of the pen or pencil in the pocket when introduced thereto.

In accordance with the present invention 20 there is provided a body member with spurs thereon adapted to engage in the cloth of the outer portion of the pocket from the exterior thereof, and also with means for attachment to a pen or pencil so that the latter may be inserted in the pocket with the 25 clip exterior to the pocket, but fixedly locked in position in the pocket against accidental removal. Applied to the clip and forming part thereof is a rockable structure forming a guard for the spurs when it is 30 desired to introduce the pencil into or remove it from the pocket while the guard is readily yieldable to permit the projection of the spurs, but is always readily manipulated to cause a housing of the 35 spurs in the guard when it is desired to remove the pen or pencil from the pocket, the guard constituting a handhole for removing the pen or pencil and simultaneously housing the spurs in a manner to 40 prevent engagement of the spurs into the cloth of the pocket, the whole operation being readily performed by one hand of the operator, and usually by the thumb and forefinger only of such hand.

45 The invention will be best understood from a consideration of the following detailed description, taken in connection with the accompanying drawings forming a part of this specification, with the further understanding that while the drawings show 50 a practical form of the invention, the latter is not confined to any strict conformity with the showing of the drawings, but may be changed and modified so long as such 55 changes and modifications mark no material

departure from the salient features of the invention.

In the drawings:—Figure 1 is a perspective view of one form of the improved clip or holder. Fig. 2 is a longitudinal section 60 of the clip or holder as applied to a pen or pencil with the latter introduced into a pocket. Fig. 3 is a perspective view of the body member of the clip or holder with the shield removed. Fig. 4 is a perspective view 65 of a structure having the essential features of Fig. 1, but somewhat modified in construction. Fig. 5 is a longitudinal section of the structure shown in Fig. 4. Fig. 6 is a detail section of the spur end of the structure of Figs. 4 and 5 showing the guard in 70 housing relation to the spurs. Fig. 7 is a view similar to Fig. 6 but showing a modified arrangement of the spur guard.

Referring to the drawings, and more particularly to the structure of Figs. 1, 2 and 3 there is shown an elongated strip 1 having near one end laterally extended curved wings, together forming a barrel 2 of incomplete cylindrical form, so as to receive 80 the body of a pen or pencil 3 and so firmly embrace it as to ordinarily hold the clip and pencil together against accidental displacement of either with respect to the other. The body member 1 extends to both sides of 85 the barrel 2, that end of the body member remote from the main portion of the body member being in the form of a tongue 4 aiding the barrel 2 in holding the clip to the body of the pen or pencil.

90 While the invention is adapted to either pens or pencils or pencil holders, it is particularly useful in connection with fountain pens and for simplicity of description, the device heretofore termed a pen or pencil will 95 be simply referred to as a pen, with the understanding that the clip may be used with any structure for which it is adapted.

99 The body member 1 for a portion of the length of the end remote from the tongue 4 has its width reduced as shown at 5, and at the extremity of the reduced end is formed with projections 6 which may be of T shape for a purpose to be described. Within the reduced portion 5 about midway of its length the body member is formed with spurs 7 which may be struck out from the material of the body member, and are shown as tapering toward the free ends. There is also provided a guard 8 in the form of an 110

2
 elongated plate having at one end an angle extension 9 terminating in a manipulating end 10. Adjacent to the junction of the extension 9 with the body of the plate 8 said extension is formed with spaced elongated slots 11 through which the pins 6 may be passed, while appropriately twisted and afterward returned to their normal condition so that their T ends are in transverse relation to the slots, whereby the plate 8 is made fast to the corresponding end of the body member 1, but is capable of rocking on the pins 6 as a hinge connection. The other end of the plate 8 from the extension 9 is formed 15 with another angle extension 12 having a slot 13 therein of a width to receive the reduced portion 5 of the body member 1, and at the end of the slot remote from the plate 8 the extension 12 terminates in a yoke member 14 in substantially parallel relation to the plate 8 although such relation is not obligatory.

When the plate 8 is flat against the corresponding face of the extension 5, the spurs 7 project through correspondingly placed passages 15 in the plate 8 to an extent to enter the front member 16 of a pocket, the back member 17 of the pocket being more or less schematically represented.

30 If it be assumed that the clip is applied to a pen 3, the elasticity of the barrel 2 will cause the body of the pen to move into engagement with the sharpened ends of the spurs 7. If, now, the pen be introduced into 35 the pocket, the front section of the pocket will readily enter between the pen and the plate 8, the spurs being inclined in a direction toward the barrel 2, readily permitting the introduction of the pen into the pocket 40 with the clip exterior thereto, but any movement of the pen out of the pocket is at once arrested by the spurs which, because of their inclined relation to the direction of movement, enter into the cloth of the front 16 of 45 the pocket, and thereby effectively anchor the pen in the pocket against any accidental removal by any force short of that destructive to the parts or to the pocket. If, however, it be desired to remove the pen 50 posely the operator by grasping the end 10 of the angle extension 9 may readily rock the guard plate 8 about the hinge formed by the pins 6, thus causing the other end of the 55 guard plate to move toward the pen until the perforated portion of the plate houses the spurs 7, this rocking movement being permitted by the length of the slot 13, and is finally arrested by the engagement of the yoke 14 against the body member 1. 60 With the spurs thus housed within the guard plate out of engagement with the front 16 of the pocket, the pen is readily removed by a lifting movement exerted on the extension 9, the end 10 of which may be simply 65 grasped between the forefinger and thumb

of one hand of the operator. The insertion of the pen into the pocket does not require a manipulation of the guard member since the spurs are then in trailing relation to the direction of movement, and do not resist the 70 insertion of the pen into the pocket.

In Figs. 4, 5 and 6 there is shown a body member 1^a formed with a barrel portion 2^a and lip 4^a, the parts being similar to those of Figs. 1, 2 and 3 except that the body member may be tapering or may be straight if so desired. The end of the body member remote from the barrel 2^a is formed with spurs 7^a as before, and between the spurs and the barrel 2^a, but close to the spurs, the body 80 member is formed with ears 18 traversed by a pivot pin 19. Inclosing the spur end of the body member is a guard member 20 shown as of ovate form, although the particular form is not obligatory. This guard 85 member is entered by the spur end of the body member through an opening 21 in one end of the guard member, and at appropriate points the walls of the guard member are pierced by passages 22 through which 90 the spurs 7^a may project. The pin 19 is carried through the walls of the guard member to hingedly connect said guard member to the body member. Furthermore, one wall of the guard member may be roughened as 95 indicated at 23 for convenience of manipulation.

The structure of Fig. 7 may in general follow the lines of the structures of Figs. 4, 5 and 6, except that there is a body member 1^b carrying a pivot pin 19^a at its extremity, while there is an ovate guard 20^a similar to the guard 20 of Figs. 4, 5 and 6 and provided with passages 21^a and 22^a and roughened at 23^a like the similar parts of 100 Figs. 4, 5 and 6. That end of the guard remote from the passage 21^a has ears 18^a therein traversed by a pin 19^a, so that the guard 20^a is hingedly or pivotally connected to the body member 1^b but at the end remote from 105 1^a in Figs. 4, 5 and 6.

By rocking the guard on its pivot connections the spurs 7^a of Figs. 4, 5 and 6 or 7^b of Fig. 7 may be caused to project into operative position through the guard, or be housed therein out of operative position, as 115 the operator may desire.

In each of the forms shown two spurs are 120 illustrated, but it will be understood that either one spur or more than two spurs may be used.

No claim is made herein to the broader aspects of the invention, since such claims are made in another application filed by us 125 on even date herewith, Serial No. 855,189 for a pen or pencil holder.

What is claimed is:—

1. A clip or holder for pens and the like, comprising a body member with means for 130

attachment to the body of the pen, said body member having projecting spurs thereon, and a shield or guard for the spurs hingedly connected to the body member adjacent to the spurs for movement with relation to the body member to sheath the spurs or to expose the spurs in accordance with the position of the shield.

2. A clip or holder for pens and the like, comprising a body member having means near one end for attachment to the body of the pen and near the other end provided with projecting spurs, and a guard or shield for the spurs hinged or pivoted to the body member at the spur end and movable about the hinge or pivot into positions housing the spurs or unsheathing them in accordance with the position of said shield.

3. A clip or holder for pens and the like, comprising an elongated strip with means at one end for attachment to the body of the pen and at the other end provided with projecting spurs and hinge or pivot means, and a shield connected to the body member by the hinge or pivot means for rocking movements thereon and also provided with passages for the spurs, the shield being movable on a hinge or pivot connection to expose the spurs or to sheath them, as desired.

4. A clip or holder for pens and the like, comprising a body member consisting of an elongated strip with means at one end for attachment to the holder to the body of the pen, and at the other end having projecting spur means, and a shield or sheath for the spur means hingedly connected to the spur end of the body member and movable toward or from the body member to expose or sheath the spur means in accordance with the position of the shield.

5. A clip or holder for pens and the like, comprising an elongated strip with a barrel at one end for receiving the body of the pen and at the other end formed with projecting spurs, and a shield for the spurs comprising a plate having passages through

which the spurs may project, said plate being hingedly connected to the body member at one side of the spurs, and at the other side of the spurs having a passage traversed by the body member and of a length to permit rocking of the shield to an extent to sheath or expose the spurs.

6. A clip or holder for pens and the like, comprising an elongated strip with a barrel near one end for embracing the pen and at the other end reduced in width and terminating in hinge or pivot pins, and in the reduced portion provided with projecting spurs, and a shield plate having angle extensions at the ends and perforations for the spurs, said shield plate near one end being traversed by the hinge or pivot pins, and held to the body member thereby and at the other end in the angle extension having a passage traversed by the reduced portion of the body member, and terminating in an angle yoke, the passage being of a length to permit rocking of the shield on the pins and the yoke operating as a stop.

7. A clip or holder for pens and the like, comprising an elongated body member with means near one end for attachment to the body of a pen and near the other end provided with spurs projecting from the body member on the same side thereof as the means for attachment of the pen, and a shield or guard carried by the body member at the spur end and having a portion on the same side of the body member as the means for attachment to the pen movable with relation to the body member to house the spurs or unsheathe them in accordance with the position of said shield.

In testimony, that we claim the foregoing as our own, we have hereto affixed our signatures in the presence of two witnesses.
